L. A. MADSON

RADIO LOUD SPEAKER

Filed March 1, 1924

FIG. 2

INVENTOR
LEO A. MADSON

By Paul, Paul & Moore
ATTORNEYS

UNITED STATES PATENT OFFICE.

LEO A. MADSON, OF ELK RIVER, MINNESOTA.

RADIO LOUD SPEAKER.

Application filed March 1, 1924. Serial No. 696,290.

- This invention relates to improvements in loud speakers particularly adapted for use to receive radio broadcasting, and more particularly relates to such loud speakers employing a radio phone unit having a vibratory plate mounted therein adapted to actuate the usual diaphragm, such for instance, as is employed in the well-known Baldwin type C unit.
- 10 The particular object of this invention is to provide a means operable in conjunction with such a phone or loud speaker unit for the purpose of equalizing the oscillations of the vibratory plate mounted therein, thereby greatly increasing the volume and strength of the incoming signals when used with a receiving set.
- 15 Other objects will appear from the following description and the accompanying drawings and will be pointed out in the annexed claims.

In the drawings there has been disclosed a structure designed to carry out the various objects of the invention, but it is to be understood that the invention is not confined to the exact features shown, as various changes may be made within the scope of the claims which follow.

20 In the accompanying drawings forming a part of this specification,

Figure 1 is a view in side elevation of a loud speaker embodying my invention;

Figure 2 is an enlarged detail sectional view of the lower portion thereof, showing a standard type of phone unit mounted therein and also showing my invention applied thereto.

In the selected embodiment of the invention here shown there is illustrated a loud speaker comprising the usual horn 4 mounted in the upper portion or cap 5 of a cylindrical housing 6, which is suitably mounted in a base 7, as shown in Figure 1. A radio phone unit, of ordinary construction, is preferably mounted in the upper portion of the cylindrical housing 6, as shown in Figure 2. The type of phone unit here shown comprises a magnet 8 having a coil 9 mounted therein by means of U-shaped brackets 11 secured thereto. The coil and magnet are secured to a perforated disk 12 which is seated in a sleeve 13 adapted to be fitted within the upper portion of the housing 6, and which is suitably secured thereto. This sleeve is preferably of non-conductive material.

The usual diaphragm 14 is shown seated on the disk 12 and has a link 15 connecting it with one end of an armature plate 16 mounted within the coil 9 in the usual manner. This plate is adapted for vibratory movement when the coil 9 is energized, as when the phone unit is functioning, thereby transmitting a similar movement to the diaphragm which causes the incoming signals to become audible. In the operation of a radio phone unit, such as the one above described, I have found that the oscillations of the plate 16 are not uniform or equal, caused by the tension of the diaphragm tending to exert a slight upward pull on the plate through the link 15. I have also found from actual experience that when the action of the vibratory armature plate 16 is equalized, the signal strength will be greatly increased, and the primary purpose of this invention, therefore, is to provide means operable in conjunction with such a unit whereby the action of the plate will be substantially equalized.

Such means preferably consists in the provision of a coil or winding 17 mounted within the housing 6 beneath the radio phone unit. This winding is encased within a suitable insulation 18 and has an iron core 19 concentrically mounted therein, having its lower end portion resting on the bottom wall of the housing and having its upper end bearing against one of the pole pieces 11 supporting the coil 9. A thin sheet of insulating material 21 is interposed between the bracket 11 and the end of the core 19 to prevent short-circuiting, and the lower end of the core is similarly insulated from the housing wall. Conductors 22 and 23 lead from the winding 17 and outwardly pass from the housing 6 through an insulating bushing 24, for connection with a suitable source of energy such as a battery.

When current is passed through the coil 17, the core 19 will become energized and will function as a magnet, scattering additional lines of force throughout the apparatus which, obviously will be greater in the intermediate portion of the casing 6 beneath the coil 9 and permanent magnet 8 of the speaker unit. As a result of the magnetic lines of force thus set up within the apparatus being relatively stronger in the intermediate portion of the casing 6 than in the upper portion thereof, the armature plate 16 will be influenced thereby and the

resultant downward pull exerted thereon will be sufficient to overcome a portion adjacent the core 19 than it is away from it, thereby influencing the armature plate 16 and causing an additional downward pull to be exerted thereon which is transmitted to the diaphragm 14 by the link 15.

In various ways the details of construction herein shown and described may be modified and still be within the scope of my invention.

I claim as my invention:

1. A radio loud speaker comprising a phone unit having a diaphragm, a magnet coil and a vibrating armature plate between the upper and lower portions of said coil and connected with said diaphragm for vibrating it when said coil is energized, and a supplementary magnet arranged adjacent to said coil and adapted to create magnetic lines of force to attract and exert a downward pull on said armature plate and thereby compensate for the tensional resistance of said diaphragm to the downward movement of said armature plate.

2. A radio loud speaker comprising a phone unit having a diaphragm, a magnet, and a vibrating armature having means con-

nected it with said diaphragm, and means for overcoming the tensional resistance of said diaphragm to the movement of said armature in one direction, said means comprising a coil connected with a source of electrical energy and a core in said coil having one end adjacent said vibrating armature.

3. A radio loud speaker comprising a phone unit having a diaphragm, a magnet coil and a vibrating armature plate between the upper and lower portions of said coil and connected with said diaphragm for vibrating it when said coil is energized, a supplementary magnet arranged beneath and adjacent to said coil and comprising an insulated winding, a core concentrically mounted therein, the upper end of said core being adjacent said coil and insulated therefrom, said supplementary magnet being adapted to create lines of force and attract said armature plate and compensate for the tensional resistance of said diaphragm to the downward movement of said plate.

In witness whereof, I have hereunto set my hand this 27th day of February 1924.

LEO A. MADSON.
